ABSTRACT

An impedance-matching resistor connected between two transmission paths of different characteristic impedances Z_o and $(Z_o + Rg)$ by the use of a series-impedance Rg , in which the impedance-matching resistor is formed into a transmission line, such as a coaxial line or a strip line, and a characteristic impedance Z_{ch} of the transmission line is varied so as to meet with a condition $(Z_o + x/L \cdot Rg)$ at a medium point spaced by a distance x from the input of one of said two transmission paths, the above mentioned one of the two transmission paths having the characteristic impedance Z_o .

IMPEDANCE-MATCHING RESISTOR

This invention relates to impedance-matching resistors used in high frequency circuits.

An impedance-matching resistor is usually employed to connect an output of a high frequency circuit, such as a pulse generator, to a load impedance. However, since impedance-matching realized in accordance with conventional techniques is incomplete, distortion of a wave form occurs in a transmitted pulse if the pulse is transmitted in a high frequency circuit.

An object of this invention is to provide an impedance-matching resistor employed for theoretically providing impedance-matching in a high frequency circuit so as to eliminate distortion of a transmitted wave form.

The principle and construction of the invention will be understood from the following detailed discussion in conjunction with the accompanying drawings, in which the same or equivalent parts are designated by the same reference numerals, characters, and symbols, and in which:

FIG. 1 is a circuit diagram illustrating an example of a conventional pulse generator using an Esaki diode (tunnel diode);

FIG. 2 is a wave form of an output of the pulse generator shown in FIG. 1;

FIG. 3 is a schematic section illustrating an embodiment of this invention applied to a coaxial cable; and

FIGS. 4A and 4B are respectively a schematic plane view and a schematic side view illustrating an embodiment of this invention applied to a strip line on a printed wiring board.

With reference to FIGS. 1 and 2, defects of conventional impedance-matching techniques are described. In a conventional pulse generator using an Esaki diode, an impedance-matching resistor R_g is usually inserted between an Esaki diode D and a load impedance Z_L as in FIG. 1. A high impedance source and a trigger pulse source are connected across terminals S_1 and S_2 . If a coaxial cable having a characteristic impedance of 50 Ohms is connected as the load impedance Z_L , a single resistor of 50 Ohms is usually employed as the inserted resistor R_g . However, since an impedance looking into the load impedance Z_L from the pulse generator is not matched with a high impedance of the pulse generator, "overshoot" L_a appears at a rear end of a pulse as shown in FIG. 2.

In this case, an impedance looking into the load impedance Z_L from two terminals of the Esaki diode D assumes values Z_L or $(R_g + Z_L)$ if the inserted resistor R_g is equal to zero or is not equal to zero respectively. As a matter of fact, the Esaki diode D and the load impedance Z_L are connected to each other by a transmission line, such as a coaxial cable or a strip line etc. Accordingly, the above mentioned overshoot cannot be eliminated if impedance matching is not performed between the Esaki diode D and the load impedance Z_L , so that the output of the pulse generator cannot be employed for a pulse device, such as a sampling oscilloscope.

In view of the situation, an impedance-matching resistor of this invention is proposed to be used for inserting between two high frequency circuits having different characteristic impedances (Z_o and $Z_o + R_g$). For example, an impedance-matching resistor of this invention is inserted between a Esaki diode D and an input (usually an connector) of a connection line (e.g.; a coaxial cable or a strip line). In this case, the characteris-

tic impedance of the impedance-matching resistor of this invention defines a transmission line having a characteristic impedance Z_{ch} and assumes an impedance $(R_g + Z_o)$ at the connection-side to the Esaki diode D , while the characteristic impedance of the impedance-matching resistor assumes an impedance Z_o at the connection-side to the connection line. Moreover, at a medium point of the impedance-matching resistor, an impedance looking into the connection line is equal to a characteristic impedance Z_{ch} of the impedance-matching resistor at the medium point as mentioned below.

Accordingly, the impedance-matching resistor of this invention is so designed that the characteristic impedance Z_{ch} is gradually varied along the longitudinal direction of this impedance-matching resistor. In this case, many types of the impedance-matching resistor can be realized in accordance with distribution types of a substance causing a series-resistance (generally a series-impedance). Examples of the impedance-matching resistor of this invention are shown in FIGS. 3, 4 and 4A. Before detailed description for the examples, theoretical principles for the characteristic impedance of the impedance-matching resistor of this invention are described below.

A characteristic impedance Z_{ch} of a transmission line is generally given as a value $Z_{ch} = \sqrt{L/C}$, if an inductance for a unit length and a capacitance for a unit length are defined as values L and C respectively. Moreover, assuming the inductance L and the capacitance C between two conductors of a transmission line are given, the characteristic impedance Z_{ch} of the transmission line can be also obtained.

A characteristic impedance Z_{ch} of a coaxial cable can be indicated as follows:

$$Z_{ch} = 138 \sqrt{u/e} \cdot \log b/a (=) \dots \quad (1)$$

In this case, references a , b , u and e are defined as a diameter of an inner conductor, one half the inner diameter of an outer conductor, and a specific permeability and a specific dielectric constant of an insulator between the inner conductor and the outer conductor respectively.

A strip line belongs to either two possible types which are the balanced type and the unbalanced type. A characteristic impedance Z_{ch} of a strip line of the balanced type can be defined as follows if the width of the inner conductor, the thickness of the inner conductor and the space between outer conductors are respectively given as values W , t and b respectively and if a value $W/(b-t)$ is equal to or more than a value 0.35:

$$Z_{ch} = Z_L = \frac{94.15\sqrt{u/e}}{\left(\left(\frac{W}{b-t} \right) + \frac{C_f}{e \cdot e_0} \right)} \quad (2)$$

In this case, a value $C_f/e \cdot e_0$ is a fringing capacitance indicated by the use of micro-micro-farad as a unit capacitance.

If the value $W/(b-t)$ is less than the value 0.35, the characteristic impedance Z_{ch} of a strip line of the balanced type can be defined as follows:

$$Z_{ch} = Z_L = 138 \sqrt{u/e} \log 4b/\pi d_o \dots \dots \dots \quad (3)$$

In this case, a reference d_o is a diameter of a center conductor of the strip line, the section of which is equivalently deemed as a circle.

A characteristic impedance Z_{ch} of a strip line of the unbalanced type can be defined as follows, if the space against an outer conductor is assumed as a value h , and if a value t is substantially equal to zero:

$$Z_{ch} = Z_L = \frac{376.6u/e}{\frac{W}{h} + \left(\frac{2}{\pi} \left(1 + \ln \left(1 + \frac{\pi W}{2h} \right) \right) \right)} \quad (4)$$

Accordingly, if a desired value of the characteristic impedance Z_{ch} is given, respective values a , b , h , W and t can be determined in accordance with the above equations (1), (2), (3) and (4).

In embodiments shown in FIGS. 3 and 4, since an impedance-matching resistor R_g is inserted between a diode D and a connector CT connected to a coaxial cable or a strip line. It is deemed that the diode D is connected, at the input of the impedance-matching resistor R_g , to a coaxial cable having a ratio a/b defined by the following relationship:

$$Z_o + R_g = 138 \sqrt{u/e} \log b/a \dots \dots \dots \quad (5)$$

In a case of a strip line, respective values W etc. can be obtained by replacing the characteristic resistance Z_o by a value $(Z_{ch} + R_g)$ in the equations (2), (3) and (4).

An impedance-matching resistor R_g of this invention is inserted between two center conductors in the generality of cases. In a case of insertion in a coaxial cable, if a whole length L of an internal resistor is divided into a number of very short sections, and if respective resistances from each division point to another end of the impedance-matching resistor are assumed as values R_1 , R_2 , ..., respective impedances looked into the load Z_o from each division point can be indicated by values $(R_1 + Z_L)$, $(R_2 + Z_o)$, ... Accordingly, respective values b_1/a_1 , b_2/a_2 , ... of a ratio b/a of respective diameters of the inner and outer conductors at each division point can be determined so as to meet with the following relationship:

$$Z_o + R_1 + K \log \sqrt{b_1/a_1} \dots \dots \dots \quad (6)$$

where $K = 138 \sqrt{u/e}$

$$Z_o + R_2 + K \log \sqrt{b_2/a_2} \dots \dots \dots \quad (7)$$

Moreover, the whole outside pattern of the impedance-matching resistor can be corrected under the above conditions.

In an example shown in FIG. 3 in which the resistance material is uniformly distributed along the whole length having a rectangular section, the following relationship is met with respect to a characteristic impedance $Z_{ch} = Z_o + R_g x/L$ if the inner diameter of an outer conductor at a division point is assumed as a value $2bx$,

if a distance from the division point to an input of a connector CT is assumed as a value x , and if the whole effective length of the impedance-matching resistor is assumed as a value L :

$$Z_{ch} = Z_o + R_g x/L = K \log \sqrt{bx/a} \dots \dots \dots \quad (8)$$

Accordingly, an outside pattern 2 of the impedance-matching resistor shown in FIG. 3 can be obtained by calculating the value bx in response to the value x varied in a region from zero to the value L .

On the other hand, if the inner diameter of the outer conductor is constant while the width $2a$ of the resistor is varied for impedance matching, a pattern of the width W_x is determined as shown in FIG. 4A so as to meet with the following relationship:

$$Z_{ch} = Z_o + R_g x/L = K \log \sqrt{b/W_x} \dots \dots \dots \quad (9)$$

In other words, the width W_x is varied along a logarithmic curve if the value b is constant.

In a case of a strip line, equations obtained by replacing the left side Z_{ch} of equations (2), (3) and (4) by a value $(Z_o + R_g x/L)$ are also satisfied. Accordingly, a required impedance-matching can be performed by adjusting the width W , the thickness t , and the distance h against the outer conductor (i.e.; a metal ground plate), and moreover the space b between the outer conductors for the balanced type only.

With reference to FIGS. 4A and 4B, an embodiment of this invention comprises an insulating board 3 usually used for printed wiring, a resistive film 1 printed or evaporatively deposited on the insulating board 3, a diode D connected to a conductor 5 on the high-impedance side of the resistive film 1, a metal terminal 4 connected to another end of the resistive film 1, and a metal ground plate 6 spaced by a space h from the insulating board 3.

As mentioned above, an impedance-matching resistor of this invention is suitable for impedance-matching two transmission paths of different impedances and useful for reliably transmitting pulses without distortion.

I claim:

1. An impedance matching resistor comprising a transmission line of predetermined length L , having an axial portion comprising one end having a characteristic impedance Z_o and another axial portion integral with the first-mentioned portion comprising the opposite end and having a characteristic impedance $(Z_o + R_g)$ to jointly define a relationship, $(Z_o + R_g x/L)$ defining a characteristic impedance at a point x along a length L of said length of transmission line.

2. An impedance matching resistor comprising a first conductor of predetermined length comprising a material having a constant resistance per unit length and a second conductor, said conductors having a configuration wherein the ratio of the transverse dimensions of said conductors at any point along the length thereof defines an exponential function, thereby jointly defining a transmission line having a linear characteristic series impedance variation linear in both directions along the length thereof, and each of said conductors having means for connecting alternatively thereto a bidirectional input and output.

3. An impedance matching resistor according to claim 11, wherein said conductors are disposed coaxially, said first conductor comprises a center coaxial conductor having a uniform width, insulation disposed between the two conductors for insulating said first conductor from said second conductor, said second conductor having a configuration whereby the ratio of its transverse dimension and the transverse dimension of said first conductor define an exponential function.

4. An impedance matching resistor according to 10

claim 2, wherein said second conductor has a uniform width and wherein said first conductor has a configuration whereby the ratio of the transverse dimension second conductor and the transverse dimension of said first conductor define an exponential function.

5. An impedance matching resistor according to claim 2, wherein said first conductor and said second conductor define a strip line transmission line.
